FRANK SHORT, OF POUGHKEEPSIE, NEW YORK

STABILIZED AIRSHIP

Application filed February 24, 1927. Serial No. 170,709.

This invention relates to airships, the broad object of which is to produce a stabilized airship that is readily controllable either manually or automatically while in flight or 5 moored. It is especially applicable to the sectional type of airship, which will herein-after be termed the flexible airship.

Among the important features of the invention are a system of ballast tanks with 10 means for distributing ballast among them, means for the control of such distribution of ballast, means for the alteration of the lift of various parts of the airship, means for the control of said alteration and means for 15 the correlation of the ballast distribution with the lift alteration control.

A further object of the invention is to so construct and combine the various elements 20 of the invention that an airship may be produced in which stability, safety and comfort are increased to a point where the airship becomes a practical commercial carrier.

With the above and other objects in view, 25 the invention consists in the novel construction, combination and arrangement herein shown, described and claimed. In the accompanying drawings:

Fig. 1 is a side elevation of an airship 30 showing diagrammatically the locations of the major elements of the stabilized airship;

Fig. 2 is a diagrammatic longitudinal cross-section of certain parts of the above figure;

Fig. 3 is a similar diagrammatic longitudinal median section of certain parts of 35 Fig. 1;

Fig. 4 is a diagrammatic view of a control system for conditions of horizontal flight;

Fig. 5 is a similar view, showing the control system of Fig. 4 set for conditions of horizontal flight, but with the central airship section over-loaded;

Fig. 6 is a similar view but showing the 45 control system set for conditions of steady climb;

Fig. 7 is a cross-section of the central section, 2, of Fig. 1;

Fig. 8 is a diagrammatic view of one form 50 of control mechanism;

Fig. 9 is a similar view of a further form of control mechanism;

Fig. 10 is a similar view of a still further form of control mechanism; and

Fig. 11 is a diagrammatic view of a further form of control system, set for horizontal flight but disturbed from normal flight conditions.

As the stabilizing system is particularly adapted to the flexible type airship, it will 60 herein be described as applied to such an airship. Fig. 1 shows such a flexible airship in which 1 is the tractor head section, preferably of rigid construction with the main power plant and the front control surfaces 65 carried thereon, 2 is a non-rigid load section and 3 is a non-rigid tail section. It is understood that these sections are preferably separable and that the load section, 2, may be omitted for light loads or that additional load sections as 2 may be added for heavier loads or longer flights.

In addition to the main power plant, 4, the front vertical control surfaces, 6, the front horizontal control surfaces, 7, and the front car, 11, the head section 1 carries tanks 21, 22 and 23, for the accommodation of ballast. It will be understood herein that the term ballast includes also fuel for the power plant, 75 oil, and other readily movable weight elements, and it is further understood that when a single system for the distribution of ballast is referred to for simplicity, a plurality of systems may be in use where a plurality of 80 kinds of ballast are in use.

Since it is anticipated that water ballast recovery will be employed in the airship to recover from the exhaust gases of the power plant water vapor in sufficient quantity to offset the approximate weight of fuel burned 90 in flight, it will be unnecessary for the airship to carry an initially large weight of water ballast. Under these circumstances, it will be desirable to have two parallel systems for ballast distribution, one for water and one for fuel. Thus, in the first part of the flight, fuel would be the main weight element to be distributed for stability control, while in the latter part of the flight, water would preferably be the principal sta- 100

bilizing element. It is further understood that although the tanks 21, 22 and 23 are designed primarily for liquid ballast of one sort or another, fluids such as the lifting gas may be employed for stabilizing purposes merely by amplifying the size of said tanks or of substituting therefor ballonets within the envelopes of the various airship sections. Solids, too, may be employed by substituting 10 conveyors for the pipe lines shown in the drawings.

The shifting of ballast is intended to care primarily for long time equilibrium conditions. For momentary disturbances of stability, aerofoils or wings, 73 and 74, are located fore and aft on the car 11, as also on other cars, 12 and 13. By changing the angles of incidence of these wings during flight, the lift or the balance or both of any 20 section may be modified; this modification being practically instantaneous, the wings 73 and 74 serve to correct the momentary disturbances and supplement the stabilizing influence of the ballast distribution system. 25 The two systems may be operated by the same control system or by separate systems; this latter is preferred and is hereinafter described.

The load section, 2, carries the car 12 and 30 the wings 73 and 74, and contains the ballast tanks 21, 22 and 23, among other things. Stream-line flaps, 10, and flexible cables attached thereto serve to hold the sections together flexibly and to produce a smooth exterior adapted to offer the minimum of air 35 resistance. The tail section 3 in addition to the rear vertical control surfaces, 8, the rear horizontal control surfaces, 9, the rear power plant, 5, which is preferably inclosed within 40 the lower vertical fin, carries the car 13, the tanks 21, 22 and 23, and the wings 73 and 74, and other elements not essential to this description.

The distribution of ballast will be described as for a liquid ballast, as the preferred form thereof. Its functions are two-fold: the fore and aft stabilization of the individual airship sections; and the stabilization of one section with respect to other sections.

The control system illustrated diagrammatically in Fig. 2 is adapted to control the fore and aft stability of an individual section, such as the load section, 2, in this instance. 55 The diagram includes the elements employed in the load car 12, it being understood that other cars, such as 11 and 13, include corresponding elements of their own stability control.

In Fig. 2, the ballast tanks, 21 and 23, are interconnected by the pipe-line 20-20^a, in which an electrically operated valve, 32, is located. Smaller pipes, 69 and 69^a, lead off of pipes 20 and 20^a, respectively, to the pump 68 (of Fig. 3) and serve to interchange bal-

last from the individual section stabilizing system to the inter-section stabilizing system of Fig. 3, or the reverse; these reduce or increase the total amount of liquid ballast equally in tanks 21 and 23 and hence do not affect the fore and aft stability of car 12. 70

A compressed air main pipe line 24 has branches 30 and 30^a leading through electrically operated valves 31 and 33, respectively, to tanks 21 and 23, and are thus adapted to introduce air pressure on the liquid 19 in case either valve 31 or 33 is opened to the air line 30 or 30^a. When closed to the air lines, these valves 31 and 33 are vented to the atmosphere—thus when valve 31 is opened and valve 32 likewise is open, compressed air on the liquid 19 of tank 21 forces some of the liquid through the pipe-line 20-20^a into the tank 23, where the pressure above the liquid surface is atmospheric, due to the vent in the valve 33. Thus, ballast is shifted from the front of the car to the rear. 80

Controlling this shift of ballast is the liquid level 35, which contains an electrically conducting liquid, such as mercury, and three contacts, 36, 37 and 38. When the car 12 is horizontal, only contact 36 touches the liquid, and there is no complete circuit through the liquid level—valves 31, 32 and 33 remain closed. Assuming a rise in the right-hand or rear end of the car 12, the liquid level makes contact with the contact 37, completing the circuit from the source of electrical energy, 26, through one wire 32^a of the branch 34, through the contact 36, through the liquid 95 of the level, through the contact 37, through the wire 31^a, through the operating mechanism of the valve 31—thereby opening this valve to air line 30—through the wire 31^b, through the operating mechanism of the liquid valve 32—thereby opening this valve to permit liquid flow in the pipe-line 20-20^a—through the wire 32^b of the branch line 34 and back to the source of electrical energy, 26. Thus, the valve openings are made as called 100 for in the preceding paragraph, and liquid ballast will flow from tank 21 to tank 23, thereby tending to restore the equilibrium of the section 12. 110

Conversely, tilting back of the car 12 115 would open valves 33 and 32, and cause a flow of ballast from tank 23 to tank 21. The control mechanism of the ballast system is preferably made more sensitive than that of the wing control system so that the temporary 120 stabilization due to aerodynamic lift of the wings may not mask the long time stabilization of the ballast system. In fact, should this precaution not be sufficient for this purpose, it is readily possible to interconnect 125 the individual section control or the inter-section control with contact-making devices controlled by the angle of incidence of the wings 73 and 74 in such a manner that even when the cars are held level by said wings 130

and the level 35 not making contact for that reason, the difference in the angles of incidence of wings 73 and 74 would cause a flow of liquid ballast between tanks 21 and 23, whereas, the difference between the angles of incidence of the wings of one section and another would cause a flow of liquid ballast from section to section. Provision is made for the above auxiliary control in the contact-stops 91, 92 and 92^a of Figs. 8, 9 and 10, wherein the wing-operating lever, 90, forms one side of the circuit and the contact-stop the other, when in contact. The necessary relays and electrical connections are readily made by one skilled in the art.

For the case of steady climb or descent during flight, the liquid level, 35, of Fig. 2 is mounted on an arm, 35^a, having a pivot, 39, and a partially supporting spring, 40. Supporting the balance of the support is the solenoid 42, which surrounds and exerts a pull on the armature 41 attached to the arm 35^a. Current flows continuously in the solenoid 42 from the top bus-bar of the source of electrical energy 26, to the pivoted arm 29 of the adjustable resistance 28, thence through the wire 27, the solenoid 42, and successively all the solenoids performing this same function for other cars in series, and thence to the lower bus-bar, preferably in the tail section, and back to the source of electrical energy, 26. By adjusting the resistance of rheostat 28, the amount of the current flowing through each of the solenoids aforesaid may be adjusted to give precisely the correct amount of assistance to spring 40 to hold the liquid level 35 level. By increasing or decreasing the resistance of 28 above or below this point, as by moving the arm 29, will change the level of all the liquid levels, 35, so shifting ballast within each section as to tend to tilt all sections through the same angle and to maintain them tilted for ascending or descending flight. A link, 29^a, may be provided to connect the arm 29 with the elevation steering mechanism of the airship, and so make the section inclination automatically adjusted by the action of the elevation steering control. The preferred method, however, would be manual control of this inclination, since the long period inclined flight would be seldom undertaken as compared with the many elevator movements incident to horizontal flight.

The inter-section stabilizing system is illustrated in Fig. 3 by diagrammatic views of the rear end of the head section car, 11, and the forward end of the load section car, 12. Other cars would have corresponding elements. The ballast tanks 22 and 22^a, in sections 11 and 12, respectively, are interconnected by the pipe-line 54, 54^a, 54^b, having the liquid valve 53 and the hand-operated valve 54^b therein. The extension pipe-line 54^d leads to following sections. The double

pump 68 may be operated in either direction of flow by the motor, 67, which is preferably under manual control, and may pump liquid ballast between the tank 22 of the inter-section stabilizing system and tanks 21 and 23 of the intra-section fore and aft stabilizing system, the ballast pumped flowing equally through pipes 69 and 69^a so as not to disturb the adjustment between tanks 21 and 23; this inter-system transfer of ballast is made within the respective sections and in no way affects the inter-section ballast distribution control.

Compressed air from the air mains, 24-24^a-24^b, may be led through branch pipes 50 and 50^a through electrically operated valves 51 and 52, respectively, to the ballast tanks 22 and 22^a. By the electrical connections, all valves are normally closed, valves 51 and 52 being then vented to the atmosphere. When either valve 51 or valve 52 is opened, valve 53 is thereby also opened to permit liquid flow between tanks 22 and 22^a.

The control of the inter-section ballast distribution is effected by the extended liquid level system 78-64-59-59^a-59^b-64^a, etc. Upright vessels, 64 and 64^a, are provided with electrical contacts 55, 56 and 57, 58, respectively. The conducting liquid in these vessels is interconnected and allowed to flow from vessel 64 to vessel 64^a and the reverse, and also to and from other similar vessels in other sections, through the connecting pipe-line 59, 59^a, 59^b, so that the level of the liquid in each vessel tends to remain at the same height with respect to the earth. The reservoir 78 serves to raise or lower this common level to adjust the sensitiveness of the control. The size of pipe used in the pipe-line interconnecting vessels 64 and 64^a may be proportioned so that friction of liquid flow will damp any tendency for liquid surges or for excessive sensitivity to instantaneous disturbances.

Should section 1 of the airship fall below the level of the rest of the sections, the vessel 64 in car 11 would be lowered below the common level of equilibrium, hence liquid would flow into vessel 64 and eventually bridge the gap between contacts 55 and 56. This would complete the circuit from the control wire 62, the branch wire 61, the contact 56, the contact 55, the electrical operating mechanism of the valve 51—thereby opening valve 51 and applying air pressure from 50 onto the liquid ballast 19 in tank 22—through the wire 63, through the operating mechanism of liquid valve 53, through the wire 65 and back to the bus-bar 25. Thus valves 51 and 53 are open and liquid ballast is forced from tank 22 to tank 22^a.

Should, however, the cause of the unbalance be a light tail section, contacts would be made in both vessels 64 and 64^a, valves 51 and 52 would both be opened, valves 53 and the

corresponding liquid valve on the pipe-line 54^a would be open, and liquid ballast would be forced from both tanks 22 and 22^a into the corresponding tank of the tail section.

5 Flexible connections with easily detachable couplings 24^a, 59^a and 54^a are provided for compressed air mains, liquid level line and liquid ballast pipe-lines, respectively. Flexible electrical cables with easily detachable 10 connections 66^a, 62^a and 25^a are provided for the electrical circuits, and are preferably combined into one unit as is common practice in railway work and the like. Hand shut off valves may be provided for all pipe-lines so 15 that liquid or pressure may not be lost when sections of the airship are separated.

A switch, 63, may be provided to open the control circuit 62 so that the interchange of ballast between sections of the airship will 20 cease during periods of climb or descent—this switch is preferably manually operated.

Figs. 4, 5 and 6 show diagrammatically the control system used in conjunction with the wings 73 and 74 on the respective sections of 25 the airship, illustrating the conditions which exist normally, with the load section 12 lower than the others and on climbing flight, respectively.

During normal flight, with the sections 30 stabilized, the liquid, 71^a, 71^b and 71^c, in the upright vessels, 75, 76 and 77, respectively, corresponding to the airship sections 1, 2 and 3 and within the cars 11, 12 and 13, respectively, maintains a level between the upper 35 contacts, 81^a, 81^b and 81^c, and the lower contacts, 82^a, 82^b and 82^c, so that no wing control circuits are closed and the adjustable wings, 73^a, 73^b, 73^c, 74^a, 74^b and 74^c, are all in a neutral position. The exact height of the liquid 40 level in each upright vessel may be regulated by screwing in or out the plunger 79 of the storage cylinder 78. If the levels are close under contacts 81^a, 81^b and 81^c, action of the adjustable wings will be more prompt when 45 a mutual vertical displacement of sections causes level liquid to flow through pipes 71 from or into any upright vessel than would be the case if the liquid level were lower, since more of the levelling liquid would have to flow 50 into an upright vessel such as 76, in the latter case, in order to bridge the gap between contacts 81^b and 82^b.

The case of the load section and its car 12 being lower than the head and tail sections is 55 shown in Fig. 5. Here, levelling liquid has flowed through pipes 71 into upright vessel 76, making the column of levelling liquid, 71^b high enough to bridge the gap between contacts 81^b and 82^b, and so cause the wings 73^b and 74^b to incline to a positive angle of incidence or one that affords upward lift from the wings in question. The intermediary mechanism may be such as that shown in Fig. 8 or in Fig. 9 or in Fig. 10, one such mechanism being adapted to operate a wing or a

pair of wings under the control of a system such as that of Figs. 4, 5 and 6, or that of Fig. 11, or other suitable level detecting system.

Inclined flight over a period of time may 70 be stably achieved as shown in Fig. 6, wherein the upper contacts, 81^a, 81^b and 81^c, have been changed in elevation with respect to the cars 11, 12 and 13, respectively, in such ratio that the contact points thereof each is at a given distance above the levelling liquid when the airship as a whole is inclined at the desired angle. Thus in Fig. 6, the liquid column 71^a has adjusted itself at the same height above the earth as columns 71^b and 71^c, but it is lower with respect to the upright vessel 75 than is liquid 71^b with respect to upright vessel 76, and relatively still lower than is liquid 71^c with respect to vessel 77. Stability control will then be with respect to this new datum level and flight will continue uniformly at the predetermined inclination angle.

The location of the wings 73 and 74 is 75 shown in Fig. 7, which is a cross section of the load section, 2. The outer envelope, 16, is preferably divided by curtains, 17, which sub-divide the lifting gas chambers into approximately equal compartments, both for 80 safety in case of leakage and for the supporting strength that these curtains 17 give from envelope 16 to car 70. Within the lifting gas compartments 14^a, 14^b and 14^c, respectively, may be air balloonets, 15^a, 15^b and 15^c, which are so proportioned that they 85 permit the lifting gas to expand as the airship rises, driving air from the balloonets and thus not losing lifting gas and lift until the maximum desired height of the airship, or ceiling, 90 is attained. The wings 73 and 74 are attached preferably toward the bottom of the car 70 and may be braced by struts 72; both attachment to the car and to the struts being pivotal in nature to permit freely adjusting the angle of incidence of these wings 95 during flight. At the bottom of the car 70 are shown in their preferred location the tanks 21, 22 and 23, which are preferably in 100 duplicate to permit the use of water ballast or fuel for stabilizing purposes as desired.

Fig. 8 shows one form of mechanism for 105 operating the wings 73 and 74—here shown for 73 only. The liquid column 71^a in upright vessel 75 may complete the electrical circuit between contacts 81 and 82 if raised 110 by inflow from pipe 71. This would be caused by a relative lowering of that part of the airship, so that it is desired to acquire more lift. Current will flow from the source of electrical energy, 83, through wire 84^a, through the operating mechanism 85 of air valve 86—thus opening the latter—through wire 84^b, through contact 81, through liquid 115 71^a, through contact 82, through wire 84 and back to the source of electrical energy, 83.

The valve 86 being open, air from the compressed air line 86^a will flow into cylinder 87, driving piston 88 and connecting rod 89 outward, thus rotating wing 73 by means of the arm 90 to a position such as 73^d which generates upward lift by reason of the motion of the wing through the air. A stop, 91 may be provided for the neutral position of the wing and an adjustable stop 92 may be 5 provided to limit the angle of incidence of wing 73. When the low condition is rectified, flow of liquid out of vessel 75 breaks the circuit between contacts 81 and 82, thus closing the valve 86, which is vented to the 10 atmosphere, and releases the air from cylinder 87. Wing 73 is so pivoted that it tends to return of itself to the neutral position—it may also have external means such as 15 springs to assist in this return to neutral. 20 Stops 91 and 92 may also serve as electrical contacts, or may carry such contacts for the tying in of the wing system by means of electrical relays with the inter-section ballast distribution system; thus if the wings of one 25 section are called upon to exert lift, these relays operate valves 51 and 53, or the corresponding valves of the proper section, and start the transfer of liquid ballast away from the section in which the wings are lifting. 30 As the effect of ballast transfer is slower than wing lift action, if the disturbance is momentarily only, very little ballast has moved before the action is stopped. If, however, there is a real unbalancing, the gradual 35 shift of ballast will relieve the wings of their lift and a stable condition will be reached. Thus, the wings act quickly and are especially suitable for short time disturbances and the ballast transfer system acts more 40 slowly and is suitable particularly for long time disturbances.

The control mechanism of Fig. 8 is arranged to permit the adjustment of the relative height of the upper contact 81 within 45 the vessel 75 by means of a cord, 81^e, running over pulley 81^f and around the winding drum of the reversible motor 81^e. Wires 81^d lead to the control cabin of the airship, preferably, and permit the operation of motor 81^e, and corresponding motors in other 50 sections, any desired number of turns and so permit of the height control of the contact 81 from a distance in order to fulfill the conditions shown in Fig. 6 for inclined flight.

More sensitive control of the wing 73 may be obtained by the mechanism of Fig. 9, wherein the liquid 71^a first makes contact with contacts 81 and 82, causing the valve 55 96 to open on the smaller cylinder 97; and then, if the disturbance of equilibrium is violent enough to cause the liquid 71^a to rise and touch contact 88, the valve 86 is opened and compressed air is admitted also to cylinder 87, giving to the wing 73 a greater

angle of incidence than 97 alone, and in consequence exerting a greater lift.

Means may also be provided, as in Fig. 10, for causing a wing to exert a depressing force or negative lift in case the part in question of the airship is above the average level. Two cylinders, 87 and 107, are provided to work in opposition to each other, the former effecting a positive lift by rotating the wing 73 clockwise, the latter a negative lift by rotating the wing counter-clockwise. The operating mechanism 105, of the valve 106, opens the valve when the current is cut off from mechanism 105; this occurs when the section rises enough to bring the level of the liquid 71^a in the vessel 103 below the contact 101, which is insulated from the vessel 103. In this instance, the source of electrical energy, 83, is connected direct to the wall of the vessel 103, which is of conducting material and serves as one of the contacts. The contact 81 serves to operate the valve-opening mechanism 85 of the valve 86, in case the section in question is low and lift upward is wanted.

The control system of Figs. 4, 5 and 6 is primarily adapted to the raising or lowering of a section as a unit with respect to the average level of the airship. Fig. 11 shows a system which combines this function with that of fore and aft balancing of the individual sections, thus enabling the wing system to supplement all the functions of the ballast distribution systems shown in Figs. 2 and 3.

Each section, 11, 12 and 13, is provided with fore and aft upright vessels, such as 111^a and 112^a, respectively. All such upright vessels are inter-connected by a pipe-line so that the liquid in each vessel tends to maintain the same level with respect to the earth as in all other vessels of the airship. These vessels are of conducting material such as metal and have connections, 100, so that the vessel may serve as one contact of each control circuit. Intermediate contacts such as 101^a and 102^a are provided and insulated from the vessels 111^a and 112^a, respectively, and serve the same function as contact 101 of Fig. 10. Contacts such as 81^a and 89^a serve the same purpose as contact 81 of Fig. 10, to cause a positive angle of incidence and lift of the corresponding wing.

Wing 73^a is controlled by vessel 111^a through the intermediary of a mechanism such as is shown in Fig. 10. Similarly, wing 74^a is so controlled by vessel 112^a, etc. With the flight conditions as shown in Fig. 11, wings 73^a and 74^a are held neutral since section 11 is in normal position. Wing 73^b is depressed since the liquid in vessel 111^b is relatively low and has broken the circuit between contact 100 and contact 101^b, thereby operating the cylinder 107 (Fig. 10). Wing 74^b is elevated and caused to give a positive or upward lift since the liquid in vessel 112^b makes contact with contact 89^b. Thus wings

73^b and 74^b tend to lower the front of section 12 and to raise the rear of this section. As section 13 is level but low, the liquid in both vessels 111^c and 112^c makes contacts with contacts 81^c and 89^c, thereby causing wings 73^c and 74^c to assume a positive angle of incidence and to give a positive lift to the section while maintaining it on a level keel.

In the above figures and descriptions, liquid levels have been used to detect level conditions and to close the appropriate control circuits. It will be understood that any means of level detection, such as the pendulum, the gyroscope and any other may be utilized in such a stabilized airship, the use of liquid levels being preferred but not an essential feature of the invention. Although liquid ballast is the preferred substance for use with the long time control system, it is understood that one skilled in the art may readily adapt the invention for the use of solid ballast or for gaseous ballast or lifting gas. It may further be possible to adapt the invention to use any material having weight, such as parts of the equipment or load, for stability control. Further, electrical means have been shown through for the execution of the control in conjunction with compressed air. It is understood that any desired means of translating the level detector's indications into action of the controlling elements may be used within the meaning of this invention. Though automatic control means have been set forth for the most part in the above, it is understood that manual control may be used to supplement automatic control or to replace it wherever desired.

I claim:

1. A sectional airship, means for flexibly connecting the sections of said airship and inter-section stabilizing means on said airship including level detecting means, intermediary operating means controlled by said detecting means for the transfer of movable weight between longitudinally separated spaces in said airship and means for the localized alteration of lifting forces.
2. A sectional airship, means for the stabilization of individual sections of said airship and inter-section means for the stabilization of an individual section with respect to other sections.
3. A sectional airship, means for flexibly interconnecting sections of said airship, means for the stabilization of individual sections of said airship and inter-section means for the stabilization of an individual section with respect to other sections.

In testimony whereof I affix my signature.

FRANK SHORT.
